UNITED STATES PATENT OFFICE.

CECIL H. TAYLOR AND STANLEY M. UDALE, OF DETROIT, MICHIGAN, ASSIGNORS TO
GEORGE M. HOLLEY, OF DETROIT, MICHIGAN.

VAPORIZER.

Application filed January 20, 1926. Serial No. 82,469.

This invention relates to an exhaust heated vaporizer of the type in which a heated rich mixture is diluted with cold air in order to make an explosive mixture at the lowest 5 possible temperature.

The specific improvement consists in providing an ignition device whereby the vaporizer is heated before the exhaust heat is available so that the initial starting period, 10 during which the heating is inadequate because of the necessity for heating up the entire mass of the engine, water jacket, etc., may be curtailed. Until the pistons and water jackets have reached their working 15 temperature it is hardly possible to put too much heat into the mixture. On the other hand, once the water jacket and pistons have reached their working temperature a good deal of the heat can be dispensed with, and 20 in fact must be dispensed with if the maximum horsepower is to be obtained. An additional feature, therefore, of this invention is that means are provided whereby the ignition device is rendered inoperative both at 25 high engine speeds and also when the vaporizer becomes heated to a certain temperature.

Figure 1 shows the application of the invention to a vaporizer of a well-known type.

Figure 2 shows the vaporizer plate.

In the figures, A is the air entrance, B is 30 an automatic air valve located therein, C is the mixing chamber which is of Venturi form. D is the rich mixture entrance, and E is a portion of the exhaust manifold. F 35 is a vaporizing plate forming one wall of said exhaust manifold. G G are the corrugations in the plate F (see Figure 2). The corrugated plate F forms with the thin cover plate H a thin primary passage through 40 which a primary rich mixture passes on its way to the mixing chamber C. A hollow cover J, supporting the cover plate H, forms the combustion chamber. This combustion chamber carries the spark plug L and the 45 nozzle S, which obtains its fuel supply and air from the primary air passage N. The fuel nozzle M discharges into this passage N, providing the necessary rich mixture for the operation of the engine. The primary 50 air communicates with the atmosphere at Q Q', the latter openings being controlled by the choke valve rod K of the valve R located in the air entrance A. A drilled passage O communicates with the drilled passage N, 55 and forms the primary mixing chamber into

which the fuel nozzle M discharges. An opening T is shown communicating with the atmosphere and discharging air adjacent to the end of the fuel nozzle S. The valve U controls the opening to the passage T, the 60 thermostat V carries the valve U. As shown the thermostat is in its upper position closing the opening T. The thermostat V is held on the pin X, which is fixed to the cover J by the spring W.

In order to facilitate starting the choke valve R is provided, the throttle rod K of which is adapted to close the opening Q'.

Operation.—Primary air is drawn in through the openings Q Q' and down the pipe B which is heated in the exhaust manifold E. Primary air then flows through the drilled passage O and aspirates the fuel issuing from the fuel nozzle M. The aspirated fuel, with the primary air, flows through the passage N and then between the plate F and the cover plate H. This mixture of fuel and air is heated by the exhaust gases circulating in E. The vaporized fuel and primary air escape through D into the mixing chamber C and so pass by the throttle Y to the inlet manifold.

A nozzle S serves as an entrance from the passage N into the hollow cover J. The fuel and air flowing through S discharges adjacent to the electrode spark plug L. This mixture is normally non-explosive and therefore will not ignite. However air, which is admitted through T under certain conditions, renders the mixture flowing through S combustible so that a flame is formed as a result of the spark from the spark plug L. This flame in J tends to heat the plate H, the burnt products escaping through E into the outlet D where they mingle with the fuel heated between the plate F and the cover H. The effect of the burner is therefore controlled by the admission of air through T. This admission is controlled by the valve U. This consists of a light disk 85 valve U which is held on its seat by the thermostat V when the temperature of the cover rises to such a point as to cause the thermostat to contract.

When the engine is cold the thermostat 105 assumes the position shown in the broken lines, which permits the valve U to open the air passage T. Under these conditions a combustible mixture is formed in the vicinity of the electrode of the spark plug L and 110

active combustion takes place in the combustion chamber J. As the speed of the engine increases, however, the depression in J increases and the weight and location of the 5 valve U is such that it rises under the influence of the incoming air and so seals the passage T. The passage T is therefore closed under two conditions:—

A. When the speed of the engine increases 10 above a certain R. P. M., so as to cause a rapid flow of rich mixture through the passage N.

B. When the temperature of the cover J increases to such a point so as to cause the 15 thermostat V to close and force the cover plate H up against the opening T. Fuel should never be burnt in J needlessly, as the fuel consumption will be made worse than it otherwise would be.

20 The function of the spring W is to protect the thermostat against permanent distortion due to its own tendency to change its shape and to close up at high temperatures.

What we claim is:—

25 1. The combination with a vaporizer of a mixing chamber, a rich mixture conduit communicating therewith, a fuel nozzle discharging into the air entrance thereof, a combustion chamber located in heating relation 30 to said conduit, means for bypassing a por-

tion of said rich mixture through and burning it within said combustion chamber, comprising a nozzle discharging into said combustion chamber, an electrode discharging adjacent to the outlet of said nozzle, an air entrance 35 also discharging adjacent to the outlet of said nozzle, an automatic air valve adapted to close said air entrance when the depression in said combustion chamber exceeds a predetermined amount. 40

2. The combination with a vaporizer of a mixing chamber, a rich mixture conduit communicating therewith, a fuel nozzle discharging into the air entrance thereof, a combustion chamber located in heating relation 45 to said conduit, means for bypassing a portion of said rich mixture through and burning it within said combustion chamber, comprising a nozzle discharging into said combustion chamber, an electrode discharging adjacent to the outlet of said nozzle, an air entrance also discharging adjacent to the outlet of said nozzle, a valve controlling the admission of air to said air passage, thermo-responsive means for controlling said 50 air valve for the purpose described. 55

In testimony whereof we affix our signatures.
